FIG. 1.

FIG. 2.

To all whom it may concern:

Be it known that we, George R. Harris and Donald E. Obbink, citizens of the United States and residents of Montrose and of Sherman Oaks, respectively, in the county of Los Angeles, State of California, have invented a new, original, and ornamental Design for Combined Sink, Ice Compartment, and Bottle Holder, of which the following is a specification, reference being had to the accompanying drawing, forming a part hereof.

Fig. 1 is a plan view of the design; and

Fig. 2 is a substantially corresponding perspective view thereof.

The dominant feature of our design resides in the full line portion of the drawing.

We claim:

The ornamental design for a combined sink, ice compartment, and bottle holder, as shown.
